Asahel Bacon
Letters Patent

The Schedule referred to in these Letters Patent and making part of the same containing a description in the words of the said Asahel Bacon himself of his improvement in Mills for grinding grain

We of America that I Asahel Bacon of Windsor Greene County State of New York have made an improvement in mills for grinding grain which is described as follows. The frame the stones the shafts and shoe are the same as in other mills. The improvement consists in suspending the upper stone or cover from an iron cap containing a hole on the top of the spindle 4 in placing the bridge tree above the stones. The spindle passes thru the cap & driven it is fastened by a screw & nut below by which means the stone or cover is suspended from the bridge tree & properly balanced. The bridge tree is placed above the stones & raised or lowered by a lever placed on the frame. A box made of iron is placed over the spindle & a cavity is made in the lower part of it to admit the head of the spindle. this is effected by making the bottom of the box in two parts and leaving a round opening in the parts for the spindle and then bring-
ing the parts together below the head of the spindle & binding them by bands of iron thus securing the top or oil pot. An opening is made in the top to pour in oil and a box is put inside of the oil pot against which the head of the spindle turns. The box is secured in the bridge tree by a central bolt and keys. The invention here claimed and desired to be secured by Letters Patent is the mode of suspending the upper or cover stone from the top or oil pot placed on the top of the spindle secured to the bridge tree above the stones and passing the spindle thru the union secured below by a screw and nut. For a further illustration of my invention I refer to the model and drawings of the same deposited in the Patent office. In witness whereof I have hereunto subscribed my name this 31st day of May 1832.
